CASING FOR ELECTRICAL EQUIPMENT

Kjeld Lehmann, Sonderborg, Denmark, assignor to
Danfoss A/S, Nordborg, Denmark

Filed June 27, 1973, Ser. No. 374,255

Term of patent 14 years

Int. Cl. D13—03

U.S. Cl. D26—5 R

FIG. 1

FIG. 2

FIG. 3

FIG. 1 is an elevational view of a casing for electrical equipment showing my new design;

FIG. 2 is a perspective view from the top of the casing; and

FIG. 3 is a perspective view thereof taken from the bottom and from the corner opposite that shown in FIG. 2.

I claim:

The ornamental design for a casing for electrical equipment, substantially as shown and described.
